UNITED STATES PATENT OFFICE

165,039

CAP

Philip Earl Young, Arcadia, Calif., assignor to George S. Bailey Hat Co., a corporation of California

Application June 8, 1951, Serial No. 15,458

Term of patent 14 years

(Cl. D3—13)

To all whom it may concern:

Be it known that I, Philip Earl Young, a citizen of the United States of America, residing at Arcadia, in the county of Los Angeles, State of California, have invented a new, original, and ornamental Design for a Cap, of which the following is a specification, reference being had to the accompanying drawings, forming a part thereof.

I claim:

The ornamental design for a cap, substantially as shown.

PHILIP EARL YOUNG,
